Inventor,
BERNHARD COLUMBUS

By his Attorney

William F. Duckel

UNITED STATES PATENT OFFICE.

BERNHARD COLUMBUS, OF NEW YORK, N. Y.

GAS-HEATER.

1,335,427.

Specification of Letters Patent. Patented Mar. 30, 1920.

Application filed May 3, 1918. Serial No. 232,347.

To all whom it may concern:

Be it known that I, BERNHARD COLUMBUS, a citizen of the United States, residing in New York, county of Bronx, and State of New York, have invented certain new and useful Improvements in Gas-Heaters, of which the following is a specification.

My invention relates to an improved heater; particularly a gas heater designed for attachment to an ordinary gas lighting fixture.

The primary object of my invention is to provide a gas heater of simple construction and made up of parts that can very easily be assembled; the said parts being relatively inexpensive to produce, whereby the heater can be made in large quantities at relatively low cost.

The above and other objects and advantages of my invention will be clearly set forth in the following description, taken in connection with the accompanying drawings, and the novel features of my improved heater will be precisely defined in the appended claims. This description, however, is explanatory only and I may of course make alterations in what is actually shown herein, especially as regards matters relating to the size, shape and arrangement of parts; to the full extent indicated by the general meanings of the terms in which the claims are expressed and by variations in the wording of the same.

On the drawings—

Figure 1 is a side view partly in section showing my improved heater mounted upon a gas fixture, and

Fig. 2 is a similar view showing another form of heater.

The same numerals identify the same parts throughout.

In the particular description of the drawings I use the numeral 1 in Fig. 1 to indicate a burner, which carries a diffusion member comprising a top 2 and a support 3, and adapted to be attached to the burner when the parts of the heater are assembled. The diffusion member is affixed to one end of the burner 1 and the other end of this burner can be attached to a gas lighting fixture 4 having a threaded nipple 5. The burner 1 includes a stem 6 having inside threads to enable it to be quickly screwed upon the fixture 4 when it is desired to put the heater in position for use. When so mounted the heater will extend from the

fixture 4 upward and the top 2, which will be of large diameter relative to the burner, will serve with the support 3 to diffuse the heat in the usual manner.

The burner 1 is made up of a flaring section 7 attached to a hemispherical or dome-shaped section 8. Preferably the section 7 is integral with the stem 6, and it is located at the end of the stem opposite the threaded end for engaging the nipple 5. The section 7 has a bead 9 extending around the rim of same and fitting into the adjacent end of the section 8 and sections 7 and 8 are united preferably by spinning or otherwise working the edge or rim 10 of the section 8 over upon the bead 9; thereby making a beaded joint between the sections. In the section 8, just above this beaded joint, I provide plurality of jet openings 11 which extend all around the burner; and from the top of this section 8, which forms the upper portion of the burner, extends a cylindrical projection, such as a boss 12. This cylindrical boss 12 is received in an opening at the center of the support 3, which thus engages it, and this boss is preferably made to fit the support tightly.

The edge of the top or deflector 2 is turned down as indicated at 13, giving this top the form of a dish shaped plate; and when the top 2 and burner 1 are united the down turned edge of the top 2 will be considerably higher than the jet openings 11. The utility of this construction is due to the fact that the jets of burning gas issuing from the openings 11 and extending directly away from the burner naturally tend to curl upward at their outer ends, and the currents of heated air created by them flowing outward toward the rim of the imperforate top 2 are turned downward by the rim 13; and thus the heat of the burner is diffused evenly through the apartment.

The nipple 5 normally carries a short piece of tubing which has the gas lighting tip on its outer end. In order to apply my heater it is only necessary to unscrew this section carrying the burner tip, remove it and apply the heater by screwing the stem 6 upon the nipple 5 as far as it will go. The usual ornamental collar 14 surrounding this nipple need not be removed.

I prefer to give the support 3 the shape of an inverted cone having an opening at its apex to engage the boss 12. This cone may be made of a sheet of metal, perfo-

rated or not, as desired, and it has projections 15 passing through openings 16 in the top 2, and then bent over, to secure it to the top.

- 5 I may also make the section 8 with an outer circumferential shoulder 17, serving as a seat for a coil of wire 18, extending from the shoulder 17 up to the support 3. This wire assists in diffusing the heat from 10 the burner 1. The shoulder 17 and wire 18 may be omitted, if desired.

In Fig. 2 the burner has a lower inverted cone-shaped section 7, and an upper section 8, secured to the lower section by bending 15 the edge of the lower section over upon the rim or edge of section 8. Above the beaded joint so provided the section 8 has a conical portion 19, with jet openings 11, and on account of the sloping surface of the portion 20 19, the jets at these openings will be directed diagonally away from the burner, or outward and upward. Above the portion 19 the section 8 has made fast thereto a cylindrical projection in the form of a collar 25 20. Around this collar is placed the lower end of a cylindrical support 21, the support engaging the collar and resting upon the burner; and the support has a cap 22 at its upper end fastened by a rivet 23 to the top 30 2. This support 21 may be perforated or not, like the support 3.

It will be seen that the construction of my improved heater is very simple as all of the parts can be stamped out and made in one 35 piece. To unite the sections 7 and 8 only a single operation is required and the burner and the diffusion member can be secured to each other simply by fitting the support over the boss 12, or the collar 20, as the 40 case may be. This mode of assembling will hold the burner and the diffusion member to each other and if they come apart anyone can at once reunite them. Of course if desired the support 3 may be soldered to the 45 burner or positively secured thereto in any other convenient manner.

Though shown in vertical position as the

most practical, the heater can of course be mounted in a horizontal or some other position as well.

50

The supports 3 and 21 are preferably perforated to let air circulate therethrough and facilitate combustion of the gas at the jet openings 11.

Having described my invention what I 55 believe to be new and desire to secure and protect by Letters Patent of the United States is:

1. In a gas heater, a flaring section having a stem and a hemispherical section 60 united to the flaring section by a beaded joint, the hemispherical section having openings adjacent said joint to provide jets extending directly away from said sections, a boss on the hemispherical section, a support 65 having the shape of an inverted cone engaging said boss, a deflector affixed to the support, and a wire encircling the hemispherical section.

2. In a gas heater, a flaring section having 70 a stem, and a hemispherical section united to the flaring section by a beaded joint, the hemispherical section having openings adjacent said joint to provide jets extending directly away from said sections, a boss on 75 the hemispherical section, a support having the shape of an inverted cone engaging the boss, and an imperforate top having downturned edges, said support having projections to engage the top, and secure the support 80 and the top together.

3. In a gas heater, a burner including a pair of sections united by a beaded joint, 85 said sections each contracting away from said joint, one of said sections having openings therethrough to provide a plurality of jets, a cylindrical projection carried by said section, a perforated support receiving said projection, and an imperforate top having downturned edges affixed to said support. 90

In testimony whereof, I have signed my name to this specification this 30th day of April, 1918.

BERNHARD COLUMBUS.
